CARRIER FOR GROUPS OF ARTICLES

Noel A. Petter, Los Angeles, Calif.

Application February 15, 1943, Serial No. 475,943

5 Claims. (Cl. 206—65)

This invention relates to a rudimentary holder, or carrier, to assist in packaging groups of small articles for shipment. Although the invention can be practiced in connection with the shipment of articles of different shape or size, it is expected to be most useful when employed in the construction of holders for groups or sets of similar articles.

In the shipment of breakable articles or small articles such as fittings, having threaded parts, or delicate parts that must be protected, it is impractical to pack them so that they have too much freedom of movement. In the case of threaded fittings the threads may become injured. For this reason, it has been the practice where such threads are exposed, to protect the threads by placing fiber tubes over the exposed portions of the threads.

One of the objects of the present invention is to provide a holder, or carrier, for the articles such as those suggested above, which will dispense with the necessity for employing fiber tubes for protecting the threads.

A further object of the invention is to provide a carrier for such articles, having a construction which will employ a minimum amount of material, and which yet will operate as a substantial protection for the articles held in the carriers.

A further object of the invention is to produce a carrier of simple construction, employing a minimum amount of material, but which readily adapts itself for holding or carrying articles of different special shapes or designs.

A further object of the invention is to provide a carrier of this kind, with a wall having sockets through which the articles to be carried may be thrust, and to construct the wall in such a way that the material of the wall adjacent the sockets, is utilized to assist in retaining the articles in the sockets.

A further object of the invention is to provide a package or carrier for the articles, which will facilitate the inspection of the articles carried thereby.

Further objects of the invention will appear hereinafter.

The invention consists in the novel parts and combination of parts to be described hereinafter, all of which contribute to produce an efficient carrier for groups of articles.

A preferred embodiment of the invention is described in the following specification, while the broad scope of the invention is pointed out in the appended claims.

In the drawing:

Fig. 1 is a perspective of a simple form of carrier embodying my invention. This view illustrates a single article carried in its socket, or pocket.

5 Fig. 2 is an end elevation of a plurality of carriers such as illustrated in Fig. 1, and the relation they will have when packed or stacked ready to be placed in a carton or container for shipment. This view is to illustrate how projecting portions 10 of the articles will be protected by the adjacent carriers.

15 Fig. 3 is a plan of one end of the carrier illustrated in Fig. 1, upon an enlarged scale and broken away. A portion of the wall of the body is broken away at the extreme end of this view to illustrate how the edges of the sockets operate to assist in holding the articles in the sockets.

20 Figs. 4, 5 and 6 illustrate another type of carrier embodying the invention and adapted to carry a small threaded fitting having a nut-like body at an intermediate point on its length, and with both of its ends threaded. Fig. 4 is a plan of this carrier with the upper wall of the body broken away so as to show a portion of the body 25 in a horizontal section, and so as to illustrate how the socket wall forms sockets to receive the articles. This view also illustrates a telescoping sleeve which holds the carrier in its closed position.

30 Fig. 5 is an end elevation of the carrier illustrated in Fig. 4, and in this view the sleeve is illustrated in dotted lines.

35 Fig. 6 is a vertical section taken about on the line 6—6 of Fig. 4, located at one of the pockets or rudimentary cells in which one of the articles is held. On each side of this cell the carrier is broken away.

40 Fig. 7 is an end elevation with certain parts broken away, and this view illustrates an embodiment of the invention somewhat similar to that illustrated in Figs. 4 to 6, but in which the articles to be packed, have a laterally projecting portion which it is necessary to protect or house within the carrier. In this view a telescoping sleeve is illustrated in dotted lines. This sleeve holds the carrier in its closed condition.

45 Fig. 8 is a side elevation of the carrier shown in Fig. 7, broken away and illustrating one of the articles in position in its pocket.

50 Figs. 9 and 10 illustrate another embodiment of the carrier somewhat similar to that illustrated in Figs. 7 and 8, but in which the pocket wall of the holder is cut and scored in a different manner, adapting it to hold articles having two 55 widely different widths or dimensions. Fig. 9 is

a plan of this type of carrier with the cover portion broken away to expose the pocket wall or socket wall which is cut and scored to adapt the carrier to hold an article shaped somewhat similar to that illustrated in Fig. 8, but in which the articles have two widely different transverse dimensions.

Fig. 10 is a section taken on the line 10—10 of Fig. 9, and also shows a portion of the carrier in side elevation. Both ends of this view are broken away.

Fig. 11 is a plan of one end of a carrier of special construction, but embodying this invention. This view illustrates a slight modification in the means employed for protecting the projecting end of the article, and illustrates how the invention may be employed to adapt the carrier for holding a relatively long thin article such as a stem, having a thread on its end which must be protected.

Fig. 12 is a vertical section taken about on the line 12—12 of Fig. 11, and further illustrating the construction of this type of carrier.

Fig. 13 is a fragmentary view showing one end of the holder illustrated in Fig. 3. This view illustrates in detail a feature that may be employed to stiffen the holding flaps.

Referring more particularly to the parts, and particularly to Figs. 1 to 3 inclusive, the carrier comprises a body 1 preferably made of light board such as cardboard, and this body is most conveniently made in one piece bent around somewhat as indicated, so as to present a rear wall 2 and a forward wall 3, the material of the forward wall having an integral extension that overlies an adjacent edge of the material to form an extension or flange 4 that extends longitudinally throughout the entire length of the carrier. The wall 3 is provided with spaced slits 5, and cross slits 6 at the adjacent dihedral angles for this wall 3, and at these slits the articles such as the threaded stem 7, are thrust into the carrier from the exterior. In doing this, tongues between the transverse slits are forced inwardly to produce flaps 8 somewhat as illustrated in Fig. 3. The edge of these flaps engage the thread on the stem 7, and will prevent it from becoming dislodged. This carrier filled with articles such as the stem 7, operates as a convenient rudimentary holder for a set of such articles, and in order to facilitate a separation of different numbers of the articles when distributing them for use from a tool room in a machine shop, I prefer to provide the carrier with a plurality of transverse score lines or weakened lines 9 on which portions of the carrier can be readily torn away when desired.

In using these carriers, they are preferably stacked together in the manner indicated in Fig. 2. An inspection of this view will show how the outer edge of each extension 4 abuts up against the rear wall 2 of the adjacent vertical tier of the carriers. In this way the projecting portion of each article 7 is carried, as it were, down in a channel or depression 10 below the upper walls 11 of the carriers. A pack or stack of these carriers assembled as indicated in Fig. 2, can be readily packed into the carton or container into which they will fit, and when so packed, the articles are efficiently held against movement that would permit them to strike each other and mar their threads.

In Figs. 4, 5 and 6 I illustrate an embodiment of the invention in which the article such as the double-threaded nipple or connector 12 is inserted by a lateral movement into its socket, or

socket 13 (see Fig. 6). In this embodiment of the invention the upper wall 14 of the body of the carrier, is provided with a plurality of transverse slits 15 with weakened lines, or score lines 16, located equidistant from the same so that when the article is pushed down into the carrier at the slit 15, the material at the score line 16 will break down like a hinge joint, and enable the material on each side of the slit to form two flaps 17 projecting down on each side of the article, and engaging it on opposite sides, and the pressure of these flaps assists in holding the devices or articles in their sockets, or pockets. If the article includes threaded nipples such as the threaded portions 12 already referred to, then if desired, slits may be formed at the points 18 (see Fig. 5) that will permit the portions of the flaps 17 adjacent the threaded nipple 12, to move inwardly independently, forming small flaps 19 as indicated in Fig. 5. These flaps can be made to project over the threaded nipple 12 so as to hold the article in place, but if desired, the carrier can be provided with a freely movable flap or outer cover wall such as the wall 14a (see Fig. 6), which can fold down across all of the pockets 13 so as to make the retention of the articles doubly secure. This cover wall 14a preferably includes an end extension, or tuck 20, which may overlie the forward wall 21 of the carrier; and a sleeve 22 may be telescoped over the entire carrier to hold this flap in place. Preferably there would be a sleeve 22 slipped over each end of the carrier.

In Figs. 7 and 8 I illustrate another embodiment of the invention in which the article 23 to be carried in the carrier, is in the form of a fitting somewhat similar to that illustrated in Fig. 4, but provided with a lateral extension 24. In this case the pocket wall, or socket wall 25 of the carrier, is constructed substantially similar to the corresponding wall of the carrier illustrated in Fig. 4, but the body of the carrier is formed with an integral extension 26 (see Fig. 7) that extends upwardly at one side and practically constitutes an extension of the back wall 27 of the holder. As shown in Fig. 7, this extension is formed of two plies of the material out of which the holder is formed, and one of these plies has a freely movable extension 28 which is capable of folding down to a closed position as indicated in Fig. 7, so as to overlie the articles in the holder, being provided with an end tuck 29 that overlies the front wall 30 of the holder. And in this closed position of the cover extension 28, a sleeve similar to the sleeve 22 can be slid over the ends of the holder. This sleeve is indicated by the dotted lines 22a in Fig. 7.

If it happens that the article to be held in the pockets in the pocket wall, has different lateral dimensions, this can be accommodated in the manner indicated in Fig. 9. In this view, 31 indicates the pocket wall, and it is provided with a plurality of spaced transverse slits 32 and cross slits 33 intersecting these transverse slits 32. These slits 33, although referred to as cross slits, extend longitudinally with the carrier. At the ends of the cross slits 33, transverse score lines 34 are provided, and at each side of the slits 33 score lines 35 are provided. Slitting the wall 31 in this way enables the tongues 36 between the slits 33, to break down into the box in the manner indicated in Fig. 10, while the material on the outer sides of the slits 33, will break down to form tongues or flaps 37 to engage the portion of the article that has the reduced lateral dimension.

In Figs. 11 and 12 I illustrate an embodiment of the invention, which is particularly adapted for

carrying a plurality of elongated articles such as stems, or small rods 38. In order to accommodate these articles, the carrier has a body 39 formed similarly to the body of the carrier illustrated in Fig. 1, and the material forming the upper wall of this body, is turned downwardly and formed into a flange 40 that overlies the bottom wall 41 of the carrier, and is secured thereto. In this way a vertical front wall 42 is formed, which may be provided with horizontal slits and vertical slits similar to the slits 5 and 6 illustrated in Fig. 1. With this arrangement, when the article 38 is shoved into place, the material of the forward wall between the horizontal slits, is bent back to form two tongues or flaps 43 which engage the opposite sides of the stem to retain it, and resist any force tending to pull the article out of the carrier. The bottom wall 41 of the carrier, extends out to a point near the tip 44 of the articles, and is formed with an inclined upwardly extending flap, or extension 45. This extension may be provided with spaced slits 46 in a vertical plane, the bottom of each slit terminating in a substantially circular socket 47 to receive the tip 44 of the stem. This flap 45, or extension, should project slightly beyond the extreme end of the tip 44. When these carriers constructed as illustrated in Figs. 11 and 12, are packed in the manner illustrated in Fig. 2, the back wall 46a of each carrier would abut against the edge of the flap 45, and possibly against the end of the stem 38 at this point. When packed in a box in this way, the flaps will hold the stems 38 against lateral movement in a horizontal plane, and also against lateral movement in a vertical plane.

In forming flaps such as the flaps 17 or similar flaps such as could be formed in connection with slits such as the slits 5 and 6 of Fig. 1, I may provide inclined, or curved, score lines 48 in the wall in which the slits 5 and 6 are formed. These score lines have their concave sides disposed toward the slit 5. If this is done, then a flap 48a (Fig. 3) is formed, that will have its base located along the curved or inclined line 48. This gives the flap a concavo-convex form that increases its holding power in resisting outward movement of the article that is held between the flaps. In Fig. 6 the flaps 17 are illustrated as though formed in this same way.

Many other embodiments of this invention may be resorted to without departing from the spirit of the invention.

What I claim is:

1. A carrier for a group of articles, having a body portion with a plurality of pockets, each pocket having a wall with an opening therethrough through which a part of each of the articles may be thrust from the exterior, so that a portion of the article projects outwardly beyond said wall; an extension projecting outwardly from

the body substantially as far as the articles project, a freely movable extension projecting from said body and capable of folding over the first-named extension into a closed position and maintained by said first-named extension displaced from the plane of said pockets, and a sleeve for telescoping over the end of the carrier for holding said freely movable extension in its closed position.

2. A carrier for holding a group of articles, having a body portion with a wall having a plurality of pockets formed therein to receive the articles, the edges of said pockets having flaps integral with said wall capable of swinging inwardly into the body when the articles are thrust into the pockets from the exterior so that the flaps associated with each pocket engage opposite sides of the article held in that pocket, said body portion being of less dimension than the articles so that a portion of each article projects outwardly beyond said wall.

3. A carrier for holding a group of articles, having a body portion with a wall having a plurality of pockets formed therein to receive the articles, the edges of said pockets having flaps integral with said wall capable of swinging inwardly into the body when the articles are thrust into the pockets from the exterior so that the flaps associated with each pocket engage opposite sides of the article held in that pocket, said body portion being of less dimension than the articles so that a portion of each article projects outwardly beyond said wall, said body having a freely movable extension capable of folding into a closed position overlying the articles to retain them in their pockets.

4. A carrier for a group of articles having a body portion with a wall having a plurality of pockets formed therethrough, each pocket operating to house a portion of each of the articles when thrust into the same from the exterior, said body portion being of smaller dimension than the articles so that a portion of each article projects outwardly on the outer side of said wall, said body portion having an extension projecting therefrom substantially as far as said articles project from said wall, said body also having a freely movable extension juxtaposed on the outer side of said first-named extension and capable of extending across the outer ends of the projecting portions of said articles so as to retain the same in their pockets, said freely movable extension having a tuck at its free end juxtaposed upon a wall of said body portion remote from said first-named extension.

5. A carrier constructed as defined in claim 4, including a sleeve telescoping over the carrier for holding the freely movable extension in its closed position.

NOEL A. PETTER.
